UNITED STATES PATENT OFFICE.

FRANK H. CLEMENT, OF ROCHESTER, NEW YORK; LOUISA S. CLEMENT, MARY G. CLEMENT, AND BENJ. H. CLEMENT, EXECUTORS OF SAID FRANK H. CLEMENT, DECEASED, ASSIGNORS TO AMERICAN WOODWORKING MACHINERY COMPANY, OF ROCHESTER, NEW YORK, A CORPORATION OF PENNSYLVANIA.

FEEDING-CHAIN.

1,371,968.

Specification of Letters Patent. Patented Mar. 15, 1921.

Application filed May 27, 1919. Serial No. 300,150.

To all whom it may concern:

Be it known that I, FRANK H. CLEMENT, a citizen of United States, residing at Rochester, in the county of Monroe and State of New York, have invented new and useful Improvements in Feeding-Chains, of which the following is a specification.

My invention relates to endless chains used in various machines requiring an automatic and continuous feed, such as wood working and similar machinery and it consists in a novel construction of traveling chains and in the application thereto of re-treating feeding dogs or lugs, by which stock of different widths and lengths may be fed in; and it further consists in means of adjusting the dogs longitudinally to the links and in accompanying devices for carrying out the invention.

In the accompanying drawings, Figure 1 is a plan view of my improved feeding chain: Fig. 2 is a sectional elevation showing the feeding dog elevated to working position and other details; Fig. 3 is a longitudinal section of the feeding dog in its lowered position: Fig. 4 is a plan view of the same: Fig. 5 is a cross section of the adjustable eccentric and Fig. 6 is an elevation of a side plate of the main links. Fig. 7 is a cross section of a track in which the improved chain may run.

Heretofore when positive feeding dogs have been required on feeding chains, it has been usual to attach them to the links by rivets or bolts. This answers for work that does not require accuracy of position, but is impracticable when a close adjustment is necessary. In the use of automatic feeding chains, especially in many wood working machines, it is often necessary to place the positive feeding dogs several links apart to receive wide or long material, but frequently every link must have a dog for narrow or short stock: furthermore in very many automatic feeders two chains are used and it is necessary that an exact transverse alignment of opposite feeding dogs be maintained in order to work the material square with one edge. I accomplish both these objects by means of the devices described below.

In the drawings A, A, Figs. 1, 2 and 6, are the side plates of the main links and

B, B, are the connecting links: C, C, are joint pins fitted tightly into the side plates 55 A and easily into links B. When the chain is assembled these pins are riveted over slightly on their ends to hold them in position. The connecting links B are hardened after fitting and pins C are also hardened 60 except the ends where they are to be riveted.

For the purpose of economy, I use cold drawn steel for the sides of the main links A, (see Fig. 6), because this material is true 65 and parallel on sides and edges and affords facility for attaching the detail parts of my invention at a low cost. The connecting link B is of a similar material and is preferably square in section and can be hardened 70 and thus adapted to work in connection with the hardened steel joint pins C. Another advantage of this chain construction is that the completed chain needs no further machining or fitting to run in a 75 grooved track E, Fig. 7, as is necessary for accurate work and thus the final cost is much less than as though each link required separate machining on sides and edges.

D is a feeding dog or lug which is fitted 80 to pass freely between the two side plate A, A, of the main links and is pivoted at one end to an eccentric 2 by means of a slot 3 and a cover plate 4. This cover plate is secured to the dog by screws 5 and is so 85 fitted as to press against the eccentric and thus hold it in adjustment. The eccentric 2 has bearings at the ends in the side plates A, A, and suitable means for revolving it are provided, as for example a screw driver 90 slot in each end, or the ends can be squared and a socket wrench used. When the eccentric is in the position shown in Fig. 5 it is neutral, but when revolved in either direction it will adjust the dog D backward 95 or forward with reference to the line of travel of the chain.

The feeding face 6 of the dog D is machined square with the line of the chain both transversely thereto, and vertically to its 100 working face, when it is in its extreme outward position as in Fig. 2. Through a slot in the dog D there passes a screw 8 which is threaded into a bar 9, Figs. 2 and 3. This bar is preferably round as shown and flat- 105 ted on one side at about the center of its

length to receive the end of a strong spring 10 which preferably surrounds the screw 8 and is thus held in position. The round ends of the bar 9 have bearings in the side plates 5 A allowing it to roll slightly as the screw 8 is adjusted and the under shoulder of the screw head is slightly crowning to accommodate itself to the swing of the dog D. By means of the parts just described, I am enabled to 10 retreat the dog D entirely below the working surface of the chain as in Fig. 3, and when it is again needed the spring 10 returns it as the screw is released. At the same time when it is desired to aline opposite dogs from 15 chain to chain, the eccentric 2 will adjust either or both dogs longitudinally until the alinement is exact.

I have described the connecting links B and joint pins C as being hardened steel for 20 durability, but it is also necessary that some means of lubrication be provided and also that such means shall be accessible for observation and attention. Inasmuch as the working face of such chains is generally exposed to receive the material to be worked, I provide oil or grease pockets 11, Figs. 1 and 2, which are preferably formed by drilling in 25 from the face of the link B at a point to meet the bearing of the joint pin C tangentially and communicate with such bearing whereby the lubricator can reach the joint pin. If oil is used, a closing plug 12 can be used to retain the oil: if grease is used the plug 12 can be a follower threaded into the pocket so as 30 to follow up the grease and push it into the bearing as it is consumed.

I am aware that feeding chains have been made up of side links and central connecting links with joint pins or rivets, but none of 40 these meet the conditions specified above.

Having thus described my invention, what I claim and desire to secure by Letters Patent is:

1. In a feeding chain, a retreating feeding 45 dog, means for retreating and returning it to working position, and means for adjusting it longitudinally on the chain, for the purposes set forth.

2. In a feeding chain, a retreating feeding 50 dog, swinging upon an adjusting eccentric, and means for adjusting the latter circumferentially, whereby the relative longitudinal position of the dog on the chain can be fixed as required.

55 3. In a feeding chain a retreating feeding dog, pivoted between the parallel sides of a main link, a screw arranged to depress the dog below the working surface of the chain,

and means for pushing the dog into working position when the screw is reversed. 60

4. In a feeding chain, a retreating feeding dog pivoted upon the side plates of a main link, an adjusting screw for swinging the dog, a nut pivoted in the main link, all coöperating substantially as described. 65

5. In a feeding chain, a retreating feeding dog pivoted upon the side plates of a main link, an adjusting screw to swing the dog, a pivoted nut to receive the screw and a spring between the dog and the nut, operating to 70 return the dog to working position.

6. In a feeding chain a retreating feeding dog pivoted upon an adjusting eccentric, a plate secured to the dog pressing hard on the eccentric whereby the latter is held in ad- 75 justment.

7. In a feeding chain, main links composed of two parallel side plates, pin-jointed near their ends, a retreating feeding dog pivoted to swing between said side plates, means for depressing said feeding dog below the working surface of the chain, means for elevating the dog to working position, an eccentric pivot supporting the dog, means for adjusting said eccentric circumferentially 80 and suitable connecting links, all operating conjointly for the purposes set forth. 85

8. The combination with a chain link of a retreatable and adjustable feed dog secured thereto and adjustable rotatable means for 90 positively actuating said dog to vary the operating height thereof.

9. The combination with a chain link of a retreatable feed dog secured thereto and adjustable both longitudinally and vertically 95 within the chain link.

10. The combination with a chain link of a retreatable feed dog pivotally secured thereto and bodily adjustable with its pivot to different operating heights. 100

11. The combination with a chain link of a pivot spanning the sides of the link and a retreatable feed dog journaled on the pivot between said sides, and a separable bearing between the pivot and dog to enable the latter to be removed without removal of the pivot or the sides of the link. 105

12. The combination with a chain link of a retreatable feed dog secured thereto, a spring biasing said dog to an upward position, and an adjustable stop in coöperation with the dog to control the height thereof. 110
